G. L. DAVIS

BOX BOARD PREPARING MACHINE

Filed Jan. 20, 1926

Inventor:
George L. Davis,

By Right Son and May

Atty.

UNITED STATES PATENT OFFICE.

GEORGE L. DAVIS, OF BROCKTON, MASSACHUSETTS, ASSIGNOR TO PACKARD CARTON COMPANY, OF BROCKTON, MASSACHUSETTS, A CORPORATION OF MASSACHUSETTS.

BOX-BOARD-PREPARED MACHINE.

Application filed January 20, 1926. Serial No. 82,496.

This invention relates to a machine for preparing a sheet or blank of box-board for bending into box form, by forming lines of weakness in the blank, and thus adapting the blank to be bent along predetermined lines. In some cases the lines of weakness are elongated cuts or incisions formed in one end of the blank by the annular cutting edge of an indenting disk of the scoring type, the other side of the blank being supported by a rotating bed roll fixed to a driven shaft. In other cases, the lines of weakness are elongated creases formed by the cooperation, with a peripherally grooved bed roll on the driven shaft, of an indenting disk of the creasing type, adapted to groove the blank without cutting it.

The invention is embodied in an improved bed roll or collar, so constructed that a plurality of like collars may be adjustably secured to a single driven shaft and cooperate either with scoring disks, or with creasing disks, with which the machine is provided, the construction of the collars being such that they are capable of a wide range of adjustment on the shaft, permitting adjacent collars to be located practically in contact with each other on the shaft, to form the lines of weakness at a minimum distance apart, and more or less widely separated from each other on the shaft, to form the lines of weakness at various distances apart.

Of the accompanying drawings forming a part of this specification,—

Figure 1 shows in perspective the body portion of a bed collar embodying the invention.

Figure 2 shows in perspective one of the rings hereinafter described, forming parts of the collar.

Figure 3 is a fragmentary view, showing in section a collar embodying the invention, and in elevation a portion of the driven shaft to which the collar is secured, a creasing disk being shown in position to cooperate with a peripheral portion of the collar in creasing a blank.

Figure 4 is a view similar to Figure 3, showing a scoring disk in position to cooperate with another peripheral portion of the collar in scoring a blank.

Figures 5, 6 and 7 are fragmentary views similar to Figures 3 and 4, and on a smaller scale, showing a plurality of cutters, and in-

denting disks, and different adjustments 55 thereof.

Figure 8 is a fragmentary sectional view, similar to a portion of Figure 3, showing a modification.

The same reference characters indicate 60 the same parts in all of the figures.

In the drawings, 12 designates a shaft constituting an element of a box-board preparing machine. The shaft may be supported in any suitable bearings, and driven by any 65 suitable means. The machine may include indenting disks 13, of the creasing type, and indenting disks 14 of the scoring type, said disks being loosely rotatable in suitable supports, and arranged to cooperate with the 70 hereinafter described bed collars supported and driven by the shaft 12.

The indenting disks may be supported by means shown by the Robinson Patent, No. 273,394, dated March 6, 1883, said means 75 permitting various adjustments of the disks.

The shaft 12 is arranged to support the bed collars in operative relation to the disks. I provide a plurality of bed collars supported by the shaft 12, and adjustable thereon to conform to adjustments of the indenting disks. Each collar has a grooved peripheral portion or zone 16, adapted to cooperate with a creasing disk, as indicated by Figure 3, and a plain peripheral portion 85 or zone 17, adapted to cooperate with a scoring disk 14, as indicated by Figure 4.

Each collar has a hub portion 18, embracing the shaft 12, and movable endwise thereon. The hub portion preferably projects 90 from one side of the collar, and is provided with a securing member, such as a set screw 19, whereby it may be detachably secured to the shaft. The opposite side of the collar is provided with a recess 20, formed to receive the projecting hub portion of another collar, so that two adjacent collars may be located in close proximity to each other, as shown by Figure 6, thus reducing to a minimum 95 the distance between two creases formed by the cooperation of two similarly adjusted creasing disks 13, with grooved peripheral portions 16 of the two bed collars. The distance between the creases may be increased more or less by adjustments of the 100 bed collars separating the collars from each other, the creasing disks being correspondingly adjusted as shown by Figure 5.

When it is desired to score instead of crease, the bed collars and the scoring disks 14 are adjusted to cause the cooperation of the scoring disks 14 with the plain peripheral portions 17, indicated by Figure 7.

Each bed collar is preferably composed of an annular body portion or section 22, integral with the hub portion 18, and two rings 23, detachably secured by screws 24 to opposite sides of the body portion. The plain periphery or zone 17 is formed on the body portion, and the periphery of each ring 23 forms a grooved zone 16.

If desired, the scoring disks 14 may be adjusted inward, by means shown by the Robinson patent, so that they will cooperate with the plain peripheral zones 17 in entirely severing instead of scoring, the machine being thus adapted to cut a sheet of boxboard into strips, in which case, the creasing disks 13 may be removed from their operative position by means shown by the Robinson patent.

It will now be seen that a machine organized as described may be readily adapted to crease, score or cut, and that a quick change from a creasing adaptation to a scoring or cutting adaptation is permitted.

When the machine is adapted for creasing, creased boxes may be made of minimum size, and considerably smaller than any heretofore made, so far as I am aware.

Instead of providing the collar with a peripheral creasing zone which is grooved, and the corresponding creasing disk 13, with a peripheral rib, I may reverse the arrangement and provide the collar with a peripheral creasing zone which includes a peripheral rib 16^a formed to cooperate with a creasing disk 13, having a peripheral groove 13^a as indicated by Figure 8.

The peripheral creasing zones 16 or 16^a of the collars are formed on detachably secured rings 23, to enable the said zones to be removed and differently formed zones substituted therefor. Said rings are preferably split or divided into sections, as indicated at 23^a (Figure 2), so that a ring may be applied to and removed from a collar without removing the collar from the shaft 12.

I employ two rings 23, in each collar, to provide a wider range of adjustment, and to hold a ring in reserve, so that in case of damage to one ring of a collar, the other ring may be substituted therefor.

I claim:

1. In a box-board preparing machine which includes a driven shaft and a plurality of board-preparing disks supported adjacent to the shaft, some of said disks being formed for creasing, and others for scoring; a plurality of bed collars supported by the shaft and having creasing peripheral portions adapted to cooperate with

creasing disks in creasing a blank, and plain peripheral portions adapted to cooperate with scoring disks in scoring the blank, the collars being adjustable lengthwise of the shaft and provided with securing means whereby they may be fixed to the shaft in any adjustable positions, so that the collars may be located to cause creasing peripheral portions thereof to cooperate with creasing disks, and otherwise located to cause plain peripheral portions thereof to cooperate with scoring disks.

2. In a box-board preparing machine which includes a driven shaft and a plurality of board-preparing disks supported adjacent to the shaft, some of said disks being formed for creasing, and others for scoring; a plurality of bed collars supported by the shaft and having creasing peripheral portions adapted to co-operate with creasing disks in creasing a blank, and plain peripheral portions adapted to cooperate with scoring disks in scoring the blank, the collars being adjustable lengthwise of the shaft and provided with securing means whereby they may be fixed to the shaft in any adjusted positions, so that the collars may be located to cause creasing peripheral portions thereof, to cooperate with creasing disks, and otherwise located to cause plain peripheral portions thereof to cooperate with scoring disks, each collar being provided at one side with a laterally projecting hub portion, having a shaft-engaging member, and at its opposite side with a recess formed to receive the hub portion of an adjacent collar, so that two adjacent collars may be located in close proximity to each other on the shaft, to reduce to a minimum the distance between creases formed by the collars and creasing disks cooperating therewith.

3. A bed collar having a plain peripheral portion formed to cooperate with a scoring disk, a creasing peripheral portion formed to cooperate with a creasing disk, and a shaft-embracing hub portion projecting from one side of the collar, and provided with a shaft-engaging member, the collar having a recess in its opposite side, formed to receive the projecting hub portion of a similar collar.

4. A bed collar comprising an annular body having a plain periphery formed to cooperate with a scoring disk, rings detachably secured to opposite sides of the body and having creasing peripheries, each formed to cooperate with a creasing disk, and a shaft-embracing hub portion integral with the body, and projecting from one side thereof, the opposite side of the body being provided with a recess formed to receive the projecting hub portion of a similar collar.

In testimony whereof I have affixed my signature.

GEORGE L. DAVIS.
